UNITED STATES PATENT OFFICE

WILLIAM W. WEBER, OF NEW YORK, N. Y., ASSIGNOR TO DIXON FABRICS CORPORATION, OF NEW YORK, N. Y., A CORPORATION OF NEW YORK

DESIGN FOR TEXTILE FABRIC OR SIMILAR ARTICLE

Application filed April 11, 1929. Serial No. 30,841. Term of patent 3½ years.

To all whom it may concern:

Be it known that I, WILLIAM W. WEBER, a citizen of the United States of America, residing at New York, in the county and State of New York, have invented a new, original, and ornamental Design for a Textile Fabric or Similar Article, of which the following is a specification, reference being had to the accompanying drawing, forming part thereof.

The figure shows a textile fabric with my new design, in plan view.

I claim:

The ornamental design for a textile fabric or similar article as shown.

WILLIAM W. WEBER.
